SPARK PLUG CONSTRUCTION

Alexander L. Robb, Pasadena, Calif., assignor, by direct and mesne assignments, to R & R Mfg. Co., Los Angeles, Calif., a corporation of California

Application December 5, 1938, Serial No. 243,994

10 Claims. (CL. 123—169)

The present invention relates generally to spark plugs for internal combustion engines and the like, and more especially to improvements in spark plugs designed to widen the satisfactory 5 operating range of a plug of given design and at the same time improve its heavy duty efficiency.

In earlier types of internal combustion engines the conditions encountered were more uniform and not so severe as the conditions found at the 10 present day. The mean operating temperatures were relatively low, measured by present standards, and so only a relatively narrow range of operating conditions was encountered. Under those conditions, spark plugs were practically 15 universal in that one type of plug would not only be suitable for most, if not all, engines, but one type was suitable for the entire range of conditions over which any one engine operated. The design of spark plugs was much simplified, the 20 chief object being to make different sizes of plugs without changing the basic style or type.

But with time, internal combustion engines have changed very much in use, style, output, and the like, and the operating conditions have 25 changed correspondingly. High compression ratios, increased horsepower, higher speeds, new fuels, have all contributed to raising greatly the mean operating temperatures and imposing much more severe operating conditions upon 30 spark plugs. These new conditions have been met by changes in spark plug design which have been, at best, compromise solutions of the new problems, and leave much to be desired in spark plug performance. These short-comings may be 35 largely grouped under two headings: inability of spark plugs to perform satisfactorily over more than a relatively narrow range of operating conditions, and inability to stand up under heavy duty conditions.

40 Many internal combustion engines of recent design are termed "hot" since they maintain a comparatively high mean temperature in the combustion chamber, thus heating the cylinder walls and parts in and around the combustion 45 chamber to much higher temperatures than formerly had been the case. Under these circumstances, and when the parts become insufficiently cooled between explosions, it is easily possible for parts of the spark plug to remain 50 above the ignition point of the fuel vapor and cause pre-ignition of the charge. This is obviously undesirable. In order to eliminate pre-ignition difficulties, there have been designed types of plugs known to the trade as "cold" plugs, 55 meaning that they do not, under conditions for

which they are designed, reach or stay at a sufficiently high temperature to pre-ignite the fuel charge.

Plugs of the "cold" type are suited only to relatively "hot" engines and fail to operate in 5 "cold" engines, in which comparatively low mean operating temperatures prevail, because the plugs are fouled easily by carbon deposits on the insulating portion of the plug. Carbon deposits either may cause a short circuit that 10 destroys the effectiveness of the spark across the spark gap, or else increase the resistance across the gap to the point where no spark at all is generated. This condition of fouling has been solved by providing a plug of a so-called 15 "hot" type, meaning that the plug retains a greater amount of heat between explosions and is maintained at a sufficiently high mean temperature to burn off carbon deposits and keep the spark gap clean.

20 The type of plug, i. e., whether "hot" or "cold," is determined by the mass of the electrode and surrounding insulating medium, usually porcelain, exposed to and heated by the gases in the combustion chamber. If the plug is of the "hot" 25 type, the mass of insulation and electrode is relatively large so that it cools slowly between explosions and retains sufficient heat to keep from fouling. The length of the exposed porcelain or other insulation is reduced to decrease 30 the mass heated when a "cold" plug is desired. The smaller mass of electrode and insulation cools more rapidly and the spark plug operates at a mean temperature lower with respect to 35 the combustion chamber mean temperature. In practice, it is necessary to make changes in the critical masses by small increments in order to provide the small gradations between extreme values, to adapt plugs to various motors, resulting in many styles with attendant increase in 40 costs and inconvenience to manufacturer, dealer, and user.

45 The requirements for "hot" and "cold" plugs are conflicting since a plug must reach certain minimum temperatures to be kept clean, but must not exceed certain temperatures to prevent pre-ignition of the fuel charge and destruction of the plug. In actual practice, spark plugs are designed to operate under a given set of conditions, and do so with satisfaction only 50 as long as the deviation from the given conditions is small because the fluctuations in temperature of the plug above and below its mean temperature are not very great. The result is that at the present time approximately twenty 55

different types of plugs ranging from the coldest to the hottest are necessary to cover the full range of operating conditions found in present day engines; and even then the plugs are not 5 sufficiently flexible or wide in their coverage to perform with high efficiency over the full range of many motors. Indeed, in some motors such as high compression, high speed racing motors, it is now necessary to use more than one set of 10 plugs. A "hot" plug is used in the engine while the engine is being warmed up; then the plugs are removed and replaced by a "cold" plug that is able to perform at the high mean temperatures of maximum output. In other words, the 15 range of conditions found in a single engine is so great that no single plug of conventional design will operate, even poorly, over the entire range of the engine. Plugs suitable for starting are destroyed and produce pre-ignition at 20 high engine output, while at low output or when starting, the conventional "cold" plug refuses to fire and does not function at all. This example shows the measures necessary to overcome the limitations inherent in spark plugs of 25 conventional design, and indicates that the flexibility of engines, such as are used in automobiles, is limited in many cases by spark plug deficiencies rather than by engine design.

It is, of course, well known that heavy duty 30 spark plugs used in racing and airplane engines have a relatively short life under these severe conditions. Porcelain is the most universally used insulating material, and the sustained high temperatures cause the glaze on the surface to 35 crack and pit, facilitating formation of carbon deposits. Also, the porcelain is so thick that it cracks from internal strains resulting from the high temperatures. These occurrences, together with pitting of the electrodes, produce relatively 40 rapid deterioration of the spark plugs at continued high temperature.

The above considerations show why known 45 types of plugs have but narrow ranges of operation, these ranges being in most instances far less than the full range of engine operating conditions. Consequently, both design and selection of a conventional plug for an engine is at best a balancing of the various demands, a compromise 50 between conflicting requirements rather than a satisfaction of the various requirements.

It is therefore a general object of my invention to provide an improved type of spark plug which satisfies the conflicting conditions imposed upon 55 plugs adapted to operate in modern types of internal combustion engines and which has a greatly increased operating range so that one type of plug not only operates efficiently throughout the entire range of conditions encountered in any one engine, but also is substantially universal in its application to all types of engines.

Likewise, it is an object of my invention to change the character of the masses or parts of a spark plug that become heated during the explosion cycle in order to remove the present inherent 65 limitations imposed upon spark plugs by conventional constructions.

Another object is to provide a spark plug having greatly increased life and efficiency.

These objects have been attained according to 70 my invention, in a spark plug having a body and an electrode assembly located centrally within the body, by providing a layer of electrical insulating material interposed between the body and the electrode assembly, in order to insulate the 75 body and electrode from each other, and an an-

nular skirt of laminated dielectric material associated with the insulating layer and surrounding the lower end of the electrode assembly. The skirt is spaced from both the body and the electrode. The insulating layer between the body 5 and the electrode is preferably of laminated dielectric material, preferably mica, although other suitable material may be used. In a preferred embodiment of my invention, this layer is in engagement for a portion of its length with the 10 body and electrode assembly and extends beyond or outside the body to form the annular skirt which surrounds the lower portion of the central electrode and is annularly spaced therefrom. Said annular skirt is likewise spaced from the 15 spark plug body and extends into the combustion chamber of the engine. Although in a preferred form the skirt and insulating layer are formed integrally with each other, they may be separate members. The skirt is of sufficiently small mass 20 that, although it becomes heated at each explosion within the combustion chamber, it cools rapidly during the expansion stroke to a temperature below that which will pre-ignite the incoming fuel charge, and consequently the skirt 25 may be said to heat and cool with substantially the same cycle as the gases within the combustion chamber. The skirt may, if desired, be reinforced by a thin metal shell around it, the mass of the shell being sufficiently small that the combined 30 masses of the shell and dielectric skirt still follow the thermal cycle of the gases within the cylinder.

How the above objects and advantages of my invention, as well as others not specifically mentioned, are attained will be more readily understood by reference to the following description and the annexed drawing, in which:

Fig. 1 is a vertical median section through a preferred form of spark plug;

Fig. 2 is a view, partly in elevation and partly in vertical section, through a modified form of spark plug;

Fig. 3 is an enlarged vertical section through the lower end of the electrode assembly and skirt 45 of dielectric material; and

Fig. 4 is a vertical median section through a variational form of plug.

The spark plug illustrated in Fig. 1 comprises a body portion 10 having a threaded barrel 11 at its 50 lower end by which the plug is screwed into a suitable opening in an internal combustion engine, a fragmentary portion of which is indicated at 12. The central electrode assembly is indicated generally at 15 and extends longitudinally 55 or axially of body 10. This electrode assembly comprises a taper plug 16 carrying wire electrode 17, which is the spark-forming portion of the assembly, and a hollow metallic tube 18 which is preferably made of stainless steel or like mate- 60 rial. Surrounding electrode 15 and interposed between it and body 10, is a layer of laminated dielectric material 20, which is preferably made of mica although any other suitable material having similar properties may be used. The electrode and surrounding dielectric material 20 are in part within an internal cavity of body 10, the cavity comprising the upper bore 24 and a slightly tapered lower bore 21. In this form of the invention, dielectric 20 extends beyond bore 21 and 70 outside body 10. Within bore 21 is a metal shell 22 which also extends downwardly below or outside the spark plug body, the shell being made of stainless steel or other similar material.

In assembling the parts of the spark plug, shell 75

22 is placed in bore 21, the walls of which converge upwardly, and the shell is swaged to fit the bore and the rounded shoulder at top end of bore 21. Then layer 20 of laminated dielectric is inserted upwardly into shell 22. Next, tube 18 is placed inside the insulating means 20 and the lower end expanded by swaging to hold the insulation tightly against shell 22. Taper plug 16 is then driven home to firmly hold the electrode assembly and shell 22 in place. The bottom edge of tube 18 is preferably spun over the shoulder of plug 16, as in Fig. 3, to lock the plug in place. The upper bore 24 of the internal spark plug cavity is enlarged and lined at 25 with dielectric material, which also is preferably mica. The annular space between the upper end of dielectric layer 20 and insulating lining 25 may be filled with a suitable insulating material, such as asbestos, as indicated at 26.

20 The central electrode assembly is connected to the ignition system of the engine by an insulation-covered conductor 28 provided with a spring terminal plug 29 that is adapted to fit snugly within the upper end of tube 18. The top end of tube 18 is preferably flared outwardly as illustrated to facilitate insertion of the conductor terminal. Some means, such as cap 30, is preferably provided on conductor 28 to close the upper end of the spark plug bore 24 in order to exclude dirt, moisture, and other substances which would interfere with proper operation of the spark plug.

In the construction shown in Fig. 1, a second or outer electrode 32 is mounted on the lower end of shell 22, the electrode being a small diameter wire bridging the shell and forming in conjunction with electrode 17 a spark gap at 33 across which the spark for ignition of the fuel charge is formed. While the illustrated construction of electrodes 17 and 32 is preferred, for reasons which will be brought out later, it will be understood that the invention is not limited to the particular size, shape, or arrangement of electrodes illustrated, but that other conventional electrode constructions may be used if desired.

Barrel 11 is counterbored at 34 to a larger diameter than bore 21 in the spark plug body. Dielectric layer 20 extends downwardly below the limits of its engagement with the body and into the counterbore, the portion of the dielectric outside the body forming an annular skirt portion 20a which surrounds the lower end of the electrode assembly but is annularly spaced therefrom. Shell 22 also extends below body 10 and surrounds a portion of skirt 20a. It will be understood that the counterbore within barrel 11 is open to and forms, in effect, a portion of the combustion chamber of the engine, and consequently skirt 20a and the lower portion of shell 22 around the skirt may be considered as extending into the combustion chamber. That portion of shell 22 which is in bore 21 and actually contacts body 10, referred to as the upper portion, may be considered to be a part of the body. It is convenient to hold shell 22 in place by placing it between body 10 and dielectric 20, but other means for fastening it in place may be employed. Since the portion of dielectric layer 20 within bore 21 is held in place between the body and plug 16, it is considered to be in engagement with the body 10, although it is not in direct contact with the body.

Fig. 2 illustrates a slightly modified form of spark plug which is the same as the form of Fig. 1 except that the electrode assembly has been

projected farther into the combustion chamber, as is desirable in some types of engines. This has been accomplished by eliminating counterbore 34 and moving the end of bore 21 down to the bottom of barrel 11. The effect is to move the whole assembly 15 down with respect to body 10 and shorten the upper end of the body. The plug still has an internal cavity comprising bores 21 and 24, and the engagement of the dielectric 20 with the body 10 terminates at the lower end 10 of bore, and skirt 20a and shell 22 project below barrel 11.

As above mentioned, insulating layer 20 and skirt 20a are both preferably made of a plurality of laminae of mica, and consequently may be combined or associated together in a single unit. To form this combined layer and skirt of laminated material, sheets of mica may be wrapped around tube 18 or an arbor a number of times to build up the desired thickness of this insulating layer, the skirt thickness then being the same. The minimum thickness of the layer, indicated as the dimension t in Fig. 3, is in general determined by the amount of insulation required between shell 22 and electrode tube 18. This minimum thickness is found in actual experience to be on the order of .015 inch, although a somewhat greater minimum is preferable in practice from the stand-point of insuring an uninterrupted operation over a long time. The maximum thickness permissible is determined by the skirt and will depend upon the type of engine in which the plug is to be used, but it will be found that, at least in some of the hotter engines, a skirt thickness materially greater than .050 inch shows a decrease in the operating range of the plug and adds nothing of value to the operation. In practice, it is preferred that the thickness t of skirt 20a be from .020 inch to .030 inch, with a manufacturing tolerance of $\pm .005$ inch. Since mica sheets may be obtained in a thickness of approximately .001 inch, the insulating layer 20 will usually be composed of approximately 20 to 25 turns of this thickness; and the number of laminae in the layer decreases, of course, as the thickness of the wrapped sheet increases. The skirt 20a and layer 20 may not be of the same thickness, if desired, although the construction shown is preferred.

Shell 22 is preferably made of sheet stainless steel having a thickness t' of approximately .010 inch, or preferably less. The length of the shell is not critical, and it may extend below the skirt, but it is preferred that it end above the bottom of the skirt by a distance, indicated at e in Fig. 3, of about one-eighth inch. The distance e may be greater in a short skirt because of the requirement of a minimum length of mica surface, discussed below. The thickness of this shell may be varied somewhat within limits, according to principles which will be discussed, although if it is less than .005 inch the shell affords very little reinforcement.

The length l of skirt 20a, that is, the distance that the dielectric material extends below or outside body 10, may likewise be varied. It has been found preferable in practice to make the dimension l approximately three-eighths inch, although plugs have been observed to work satisfactorily with variations in this dimension ranging from approximately one-eighth inch to approximately five-eighths inch. The length of skirt is subject to the requirement that there should be at least one-fourth inch measured along the mica surface separating the central electrode from the

body, and the measurement in this case is made from the bottom of shell 22 around the end of skirt 20a to the end of tube 18. If this is less than one-fourth inch, electricity leaks over the 5 mica surface to the body.

In general, it may be said that the skirt thickness should be determined with the skirt length in mind, in order to keep the volume or mass of material exposed to the combustion chamber within 10 desired limits. For example, the ratio of l/t in a preferred form, where l equals .375 inch and t equals .030 inch, is about 12.5. Most satisfactory results are secured when the ratio l/t is kept between 4 and 25. If the ratio is larger, 15 the skirt is apt to be too thin or too long; and if too long it may melt or be broken away until it is shortened enough that it comes within the range. If the ratio is less than 4, the skirt may be too short to prevent electric leakage from the 20 central electrode, or the thickness may be so much that the mass is too large to secure maximum advantages of the invention. When a shell 22 is used, its mass must also be allowed for in designing the skirt. There T equals $t+t'$, the 25 ratio I/T is preferably between 3 and 25.

It is preferred to make insulating means 20 and skirt 20a integral with each other because it is easy to associate properly the two elements. It is, however, possible to make the two elements as separate members of different materials, and in this case the skirt is still associated with and contiguous to the insulating means which insulates the body from the central electrode assembly. An embodiment of this latter type is shown in Fig. 4 in which the central electrode assembly is a single formed electrode 40 extending longitudinally of the plug body 41 and insulated therefrom by suitable insulating means 42, shown as a molded porcelain core or the like. The core 42 and electrode 40 are placed within an internal body cavity, the lower portion 43 of which is a tapered bore. Between the tapered walls of bore 43 and a conical portion of core 42, is held a skirt 45 of laminated mica or other like material. Tapering these parts holds the skirt firmly when the insulating core 42 is drawn downwardly within the body cavity by turning down nut 46 which engages body 41 with a screw thread. Other suitable means of holding the skirt in place may be employed. The lower end 40a of the central electrode is the sparking portion and forms a spark across an air gap to electrode 47 on body 41.

As before, the skirt 45 extends beyond or outside body 41 into that portion of the combustion chamber formed within the counterbore 34 of barrel 41a. Skirt 45 is in direct contact with both insulating means 42 and body 41 at its upper end for a sufficient length to hold it in place, but is entirely separate from the insulating means. Skirt 45 is in all essentials the same as skirt 20a as the length, thickness, material, and laminated construction of skirt 45 are all subject to the same considerations as are set out above in connection with Figs. 1 to 3. Shell 22 has been omitted.

The advantages of this novel spark plug construction are derived primarily from the use of a skirt which, together with the surrounding shell if one is used, has a relatively small mass, and also is of laminated nature. These advantages will be more readily understood if the operation of a spark plug having a skirt composed of only a single mica sheet (about .001 inch) is first considered. Tests of a spark plug of this

nature disclose that the mica skirt melts back to within a very short distance of the spark plug body, indicating that the skirt of this small mass has reached temperatures of approximately 3000° F. during or shortly after the explosion in the combustion chamber. Yet this skirt cools sufficiently that no detonation or pre-ignition of incoming fuel charge occurs. The results indicate that, although the skirt has such small mass that it becomes heated far above the ignition 10 point of the fuel at each explosion within the cylinder, it cools below the ignition point as the gases are exhausted so that it is below the ignition point when the new fuel charge enters the cylinder. This rapid heating and cooling may 15 be said to take place at the same rate or at the same cycle as the heating and cooling of gases within the combustion chamber. To summarize the conditions, it has been found that a skirt composed of a single sheet of mica is of such 20 small mass that it closely follows the thermal cycle within the combustion chamber.

A plug having a skirt formed of only a single sheet of mica as mentioned, functions perfectly for awhile but has a relatively short life, and 25 this life may be extended by increasing the number of sheets of mica in the skirt. While the rate of heating and cooling is naturally somewhat modified by adding to the number of mica laminations, yet it has been found that a laminated 30 skirt, even though composed of twenty or more laminae, behaves much more like a single sheet than like a solid homogeneous body of similar dimensions. In other words, the laminated skirt of the dimensions given still substantially follows the thermal cycle of the combustion chamber, and does so much more closely than a non-laminated or single lamina skirt of the same 35 dimensions as to produce greatly improved operation. As a consequence of this laminated 40 construction, it has been found by experiment that a spark plug construction within the general limits set out above becomes sufficiently heated during each explosion stroke to keep the 45 skirt 20a entirely clear of any carbon deposits that would interfere with the plug's efficiency, and at the same time the plug cools with such rapidity that there is no danger of pre-ignition. This condition has been observed to hold true under a very wide range of operating conditions. 50 Consequently, a single plug of this type will cover substantially all, if not all, of the operating conditions found in engines of modern types. It will be realized, of course, that the dimensions and mass of the skirt and surrounding shell may 55 be varied somewhat according as a plug may be designed especially to operate in relatively hot or cold ranges, or to increase the range of the plug to meet new conditions not found at present in engines. As mentioned above, any 60 types of electrodes 17 and 32 may be used, but when the plugs are designed for service in hot engines, it is preferred to use platinum wire of about .010 to .020 inch diameter. These fine wire electrodes follow the heat cycle in the cylinder 65 and do not cause any pre-ignition.

Another advantage of the laminated construction of dielectric layer 20 is that although the wide operating range of one or a few thin sheets of mica is obtained, yet there is not the disadvantage that the mica becomes hot enough to melt. There is sufficient transfer of heat from the outer laminae to the inner ones that even under normally severe conditions no appreciable melting of skirt 20a is found to happen.

A further advantage of the laminated construction of skirt 20a is the elimination of internal strains resulting from temperature changes. Each lamina is sufficiently thin that no appreciable internal stresses are set up even at the extremely high temperatures encountered, and because of the laminated construction there are but little greater stresses set up in the skirt as a whole. Consequently, the destruction or 5 deterioration of the insulation from heat stresses is substantially eliminated as compared with a solid homogeneous body of equal mass and dimensions.

As an example of the ability of this plug to 10 perform under all conditions, plugs of this type have been found to perform perfectly at high output in an automobile engine using gasoline of 60 octane rating without pre-ignition when the motor had become sufficiently overheated 15 that other plugs in the engine, of a conventional type in the best suited heat range, would miss fire or pre-ignite the charge. In the same engine it was found impossible to foul my improved plugs, by short-circuiting individual plugs and 20 continuing to run the motor, or by coasting down hill under compression with the ignition off. Under these conditions my novel plugs fired immediately and performed perfectly whereas the conventional plugs had to be removed and cleaned 25 before they would fire at all.

The long life of my improved spark plug is 30 illustrated by comparative tests run in stationary engines of the Hesselman type using Diesel fuel and run continuously over the entire output range. In engines of this type conventional spark plugs of the best heat range available have been found, under the service conditions of the tests, to average not over 100 hours total service, many 35 plugs breaking down much sooner, while plugs constructed in accord with the present invention have demonstrated their ability to perform perfectly after more than 500 hours continuous service under the same conditions and in some cases after as much as 1000 hours continuous service. Comparison of the ease of fouling has been made by removing the ignition wire from a plug and allowing the engine to run. Whereas the best available plugs of ordinary types almost invariably foul so badly as to require removal after a few revolutions, my improved type 40 of plug has, after being shorted out for over an hour, immediately fire, cleaned itself of any deposits of oil or carbon, and resumed operation without any impairment.

From the foregoing it will be seen that the 45 dimensions and limitations discussed are not definite or critical, but only serve to indicate that zone or range within which the maximum advantages are secured from my improved construction. Similar advantages, but to a lesser degree, can be obtained at either side of the boundaries indicated, but it is believed that the various considerations governing design set out above, while individually are not fixed or definite, 50 taken as a whole define with certainty the particular construction and advantages of my invention. Because changes in design, size, and shape of parts may be made, it is desired that the foregoing description be considered as illustrative of rather than limitative upon the claims 55 appended hereto.

I claim:

1. In a spark plug for an internal combustion engine or the like, the combination of a body provided with an internal cavity; an electrode as-

sembly located within said cavity and provided with a sparking portion at its lower end; electrical insulating means interposed between the electrode assembly and body to insulate one from the other; and an annular dielectric skirt 5 associated with said insulating means and surrounding the lower end of the electrode assembly but spaced therefrom, said skirt comprising a longitudinally laminated structure of dielectric material and having a thickness not over about .030 10 inch and a length-to-thickness ratio between 4 and 25.

2. In a spark plug for an internal combustion engine or the like, the combination of a body provided with an internal cavity; an electrode assembly located within said cavity and provided with a sparking portion at its lower end; electrical insulating means interposed between the electrode assembly and body to insulate one from the other; an annular dielectric skirt 15 associated with said insulating means and surrounding the lower end of the electrode assembly but spaced therefrom, said skirt comprising a longitudinally laminated structure of dielectric material; and a relatively thin metallic shell surrounding at least 20 a portion of the skirt to reinforce and protect the latter.

3. In a spark plug for an internal combustion engine or the like, the combination of a body; an electrode assembly located centrally of the 30 body; and a layer of electrical insulating material interposed between the electrode assembly and body and for a portion of its length in direct engagement with the body and electrode assembly to insulate one from the other, said layer 35 being formed of laminated dielectric material and extending beyond the body and into the combustion chamber of the engine to form an integral annular skirt portion annularly spaced from both the body and the central electrode 40 assembly.

4. In a spark plug for an internal combustion engine or the like, the combination of a body; a central electrode assembly surrounded by the 45 body; electrical insulating means interposed between the body and electrode assembly, the insulating means comprising a laminated mica layer surrounding the electrode assembly and extending beyond the limit of its engagement with the body to form an annular skirt portion that is 50 spaced from both the body and the central electrode assembly; and a thin metallic shell surrounding only a part of the skirt to reinforce and protect the latter but leaving the lower end 55 of the skirt exposed.

5. In a spark plug for an internal combustion engine or the like, the combination of a body; a central electrode assembly surrounded by the body; electrical insulating means interposed between the body and electrode assembly, the insulating means comprising a dielectric layer surrounding the electrode assembly; and an annular dielectric skirt 60 associated with said insulating means and surrounding the lower end of the electrode assembly but spaced from both the body and the central electrode assembly, said skirt being of sufficiently small mass that it heats and cools at substantially the same cycle as the gases 65 within the engine combustion chamber.

6. In a spark plug for an internal combustion 70 engine or the like, the combination of a body; an electrode assembly located centrally of the body; and a layer of electrical insulating material interposed between the electrode assembly and body and for a portion of its length in engagement 75

with the body and electrode assembly to insulate one from the other, said layer extending beyond the body and into the combustion chamber of the engine to form an annular skirt portion annularly spaced from the central electrode assembly, said skirt portion being of sufficiently small mass that it becomes sufficiently hot at each explosion within the combustion chamber to burn off carbon deposits and becomes sufficiently cool between explosions not to ignite the new fuel charge in the chamber.

7. In a spark plug for an internal combustion engine or the like, the combination of a body; a central electrode assembly surrounded by the body; electrical insulating means interposed between the body and electrode assembly, the insulating means comprising a dielectric layer surrounding the electrode assembly and extending beyond the limit of its engagement with the body to form an annular skirt portion that is spaced from both the body and the central electrode assembly; and a relatively thin metallic shell surrounding at least a portion of the skirt to reinforce and protect the latter, said skirt portion and metallic shell together being of sufficiently small mass that the skirt becomes sufficiently hot at each explosion within the combustion chamber to burn off carbon deposits and becomes sufficiently cool between explosions not to ignite the new fuel charge in the chamber.

8. In a spark plug for an internal combustion engine or the like, the combination of a body; an electrode assembly located centrally of the body; and a layer of electrical insulating material interposed between the electrode assembly and body and for a portion of its length in direct engagement with the body and electrode assembly to insulate one from the other, said layer being formed of laminated mica material and extending beyond the body and into the combustion chamber of the engine to form an annular skirt

portion annularly spaced from both the body and the central electrode assembly, said skirt portion being of sufficiently small mass that it becomes sufficiently hot at each explosion within the combustion chamber to burn off carbon deposits and becomes sufficiently cool between explosions not to ignite the new fuel charge in the chamber.

9. In a spark plug for an internal combustion engine or the like, the combination of a body; a central electrode assembly surrounded by the body; electrical insulating means interposed between the body and electrode assembly, the insulating means comprising a laminated mica layer surrounding the electrode assembly and extending beyond the limit of its engagement with the body to form an annular skirt portion that is spaced from both the body and the central electrode assembly; a thin metallic shell surrounding only a part of the skirt to reinforce and protect the latter but leaving the lower end of the skirt exposed; and an electrode mounted on the shell in a position to form with the central electrode assembly a spark gap.

10. In a spark plug for an internal combustion engine or the like, the combination of a body provided with a longitudinally extending cavity having a bottom section of smaller diameter than the upper section; an insulating liner within the upper section of said body cavity; a metallic shell lining the lower section of the cavity; a layer of insulation within the shell and extending both above and below the lower section of the cavity; a metal tube inside the insulation layer extending to near the top of the insulation layer and adapted to receive an electric conductor at its upper end; a plug carrying an electrode inside the lower end of the tube and extending below the tube; and a second electrode mounted on said shell and forming a spark gap with the first-mentioned electrode.

ALEXANDER L. ROBB.
